CONDIMENT HOLDER

Robert M. Currie, Carbonado, Wash.

Application November 24, 1934, Serial No. 754,567

2 Claims. (Cl. 65—45)

My invention relates to improvements in condiment holders and has for its object to provide a holder divided by a central partition to provide separate compartments, each compartment being adapted to contain a different condiment and a cover for the compartments having means associated therewith for controlling the discharge of the condiment from each compartment.

A further object of the invention is to provide an article of the above-mentioned character which is simple and durable in construction, reliable and efficient in use and inexpensive to manufacture.

Other objects and advantages of the invention will be apparent during the course of the following description.

In the accompanying drawing, forming a part of this specification and in which like numerals are employed to designate like parts throughout the same.

Fig. 1 is a side elevation view of the holder,
Fig. 2 is a top plan view of the same,

Fig. 3 is a horizontal section taken on line 3—3 of Fig. 1,

Fig. 4 is a vertical section taken on line 4—4 of Fig. 1, and,

Fig. 5 is a vertical section taken on line 5—5 of Fig. 2.

In the drawing, wherein for the purpose of illustration, I have shown a preferred embodiment of my invention, the numeral 5, denotes the body of the holder which is circular in cross section having a central vertical partition 6, dividing the body into separate compartments 7 and 8, each compartment being adapted to contain a separate condiment, such as salt and pepper. A cover 9 is provided for the body having a horizontal wall 10 adapted to close the upper ends of the compartments 7 and 8. The wall 10 is spaced from the top wall 11 of the cover and extending across the center of the space between the walls 10 and 11 is a partition wall 12 which divides the space into separate chambers 13 and 14, which, respectively, align with the compartments 7 and 8, when the cover is fitted on the body. The side walls of the cover extend below the wall 10 and fit over the upper edge of the body and at opposite sides are provided with inwardly projecting lugs 15, which engage in the bayonet shaped slots 16 formed in the outer walls of the body. The wall 10 in each of the chambers 13 and 14 is provided with an opening 17, normally closed by the hemispherical shaped valve member 18 attached to one end of the pivoted lever 19. The lever 19 is pivotally mounted, in-

termidate its ends, to the bracket 20 attached to the wall 10 and its opposite end extends through a slot 21 formed in the side wall of the cover, a finger piece 22 being formed integral with the extended end of the lever for manually depressing the lever to raise the valve member 18. A spring 23 is disposed between the lever 19 and wall 10 which exerts a tension on the lever to hold the valve member in a closed position. The top wall 11 of the cover is provided with a series of perforations 24 over each of the chambers 13 and 14, the perforations on one side being smaller than the perforations on the other side.

In use, the compartments 7 and 8 are filled with different condiments, such as salt and pepper and then the cover 9 is fitted in place so that the wall 10 covers the upper ends of the compartments. When the cover 9 is in place the chambers 13 and 14 are alined with the compartments 7 and 8, so that when the valve members 18 are opened the condiments from the compartments are discharged into the chambers and are dispensed from the chambers through the perforations 24 in the top wall of the cover. The valve members 18 are opened by depressing the levers 19, and by selectively operating the levers either kind of condiment may be dispensed from the holder. When the levers are released, the valve members are automatically closed by the action of the springs 23 on the levers.

It is to be understood that the form of my invention herewith shown and described is to be taken as a preferred example of the same and that certain changes in the shape, size and arrangement of the parts may be made without departing from the spirit of the invention or the scope of the subjoined claims.

Having thus described my invention, I claim:

1. A condiment holder comprising a body divided by a vertical partition into separate compartments, a cover for the body having spaced top and bottom walls, a partition disposed between the top and bottom walls of said cover forming separate chambers adapted to align with the compartments of said body, the bottom wall of each chamber having an opening therethrough, a ball valve member in each of the chambers normally seated in the opening in the bottom of the chambers, a lever rockably mounted in each of the chambers having one end connected to said valve member and its opposite end extending through the side of said cover, for actuating said lever to raise said ball valve from its seat and spring means normally holding said

ball valve seated, the top of each chamber being provided with perforations.

2. A condiment holder comprising a body divided by a vertical partition into separate compartments, a removable cover for said body having separate chambers therein adapted to aline with said compartments, each of the chambers having an opening in the bottom thereof establishing communication between said chambers and compartments, a ball valve member in

each of said chambers normally seated in the openings in the bottom thereof, and a lever rockably mounted in each of said chambers having one end connected to said valve member and its opposite end extending through the side of said cover, for rocking said levers to raise said valve member from its seat, the top of each chamber having perforations therethrough. 5
